UNITED STATES PATENT OFFICE.

THOMAS CROSSETT, OF BROOKLYN, NEW YORK.

METHOD OF MAKING U-PACKING.

1,386,601.

Specification of Letters Patent.

Patented Aug. 9, 1921.

Application filed May 29, 1919. Serial No. 300,652.

To all whom it may concern:

Be it known that I, THOMAS CROSSETT, a citizen of the United States, and resident of borough of Brooklyn, in the county of Kings 5 and State of New York, have invented certain new and useful Improvements in Methods of Making U-Packing, of which the following is a specification.

Heretofore, so far as I am aware, U-packings have been made by means of a two-part die, one part of which has an annular groove and the other part has an annular projection to force a corresponding portion of a disk of leather into said groove, leaving 10 an intermediate portion of the disk to be cut out. Such forcing of the leather necessarily stretches the parts thereof that enter the groove to such an extent as to injure the leather with consequent weakening of it, 15 whereby the U-packing so formed will crack in places and wear out quickly and will permit leakage at the joint the packing is intended to make tight. Another disadvantage is that the aforesaid stretching of the 20 leather has the effect to make the packing thinner at the bottom of its U-groove than at the sides, rendering the packing weakest at the bottom of the U-groove where it should be the strongest.

25 The object of my invention is to produce U-packing without stretching the material thereof into a groove in a die and without injuring the material.

In carrying out my invention I first fold 30 a portion of a disk of leather or other suitable material over a centrally disposed annular block or disk member by means of an outer loose ring forced against the part of the disk that protrudes beyond the block; 35 then, with such ring in place, I flare outwardly the skirt portion of the disk, and by means of another loose ring, larger in diameter than the first named ring, I force said skirt portion of the disk around the outer 40 surface of the first named ring, thereby forming the corresponding portion of the disk into U-shape. When said block and rings are removed from the folded material 45 the intermediate portion of the material will be removed and the edges of the U-shaped ring so produced will be trimmed to effect the desired dimension of the resulting U-packing. Instead of unduly stretching the material for the packing first over the inner 50 block and then over the first ring used, said material is more or less crowded to-

gether or compacted at the portions that form the side walls of the U-packing, and since the portion that forms the bottom of the U-shape is merely folded over the edge 60 of the first named ring, said bottom portion is usually more or less thicker than the side walls, giving increased strength at the bottom of the packing groove. The leather required for the packing need be of no greater 65 thickness than that required in the finished product.

In the accompanying drawings I have illustrated means for producing my improved U-packing in accordance with my 70 novel method, wherein—

Figure 1 is a central sectional view illustrating the first step in folding the material for the packing;

Fig. 2 is a similar view illustrating the 75 parts ready for final folding of the material;

Fig. 3 illustrates the parts of the mold or die assembled and the material therein folded in U-shape;

Fig. 4 is an edge view of the folded material;

Fig. 5 is a cross section of Fig. 4;

Fig. 6 is a partly sectional view illustrating my improved U-packing and

Fig. 7 is a plan view of the three concentric members of the mold.

Similar numerals of reference indicate corresponding parts in the several views.

The numeral 1 indicates the inner member 90 of the mold or die, shown in circular block-like form, 2 indicates a ring of greater diameter than member 1, to fit around the same, and 3 indicates an outer ring of greater diameter than ring 2 to fit around 95 the latter. A disk 4 of leather or other suitable material for the U-packing is placed centrally upon member 1, with the marginal portion of the disk protruding beyond said member, as indicated by the dotted lines in 100 Fig. 1. Said disk will be of suitable diameter to produce the desired packing. Mold 1 will be placed upon a suitable support and ring 2 will be placed against the disk outside of member 1 and forced along the outside of said member to fold the material thereover, as illustrated in Fig. 1. The operation described produces a substantially cup-shaped part of the material having an annular wall extending substantially at right angles to the mid-portion 4^a and with a skirt-like portion 4^b of the material protruding 105 110

beyond ring 2. By preference a plate 5 is secured against the mid-portion 4^a of disk 4 and may be tightly clamped by a bolt or screw 6 passed through holes in said plate 5 and disk and through a registering hole 1^a in block member 1, whereby the material at 4^a is securely retained and the ring 2 is retained in place, said plate forming an abutment for ring 2 for the next step of the operation. The parts assembled as stated may be reversed in position for the next step as indicated in Fig. 2, although such reversal is not necessary. The skirt portion 4^b of material 4 may be pressed outwardly and backward in the direction of ring 2 to receive the ring 3 as shown in Fig. 3. Ring 3 is next forced against the skirt portion 4^b and around the ring 2 to fold the portion 4^b reversely along and around the exterior 20 of said ring, the material being folded against the edge 2^a of ring 2 substantially as shown in Fig. 3, whereby the material is folded in so-called U-shape in annular form with the walls spaced concentrically outside 25 of the central portion 4^a. In case the material 4, such as leather, shall have been soaked in water, oil, or other liquid, it is preferable to allow the material to dry with the mold parts assembled thereon, as in Fig. 3. When 30 the mold parts have been removed from the folded material the central portion 4^a will be cut away producing a U-shaped ring, and the edges of the walls of said ring will be trimmed to suit requirements, resulting in 35 the completed U-packing in ring-like form as shown in Fig. 6.

The material is not merely stretched to fold it over the edge of mold member 1, nor to fold it over the edge 2^a of ring 2, since 40 in both instances the extended portion of the material is free, and at the folded part 4^a the material is folded over the edge 2^a of ring 2 without being crowded or stretched whereby in the finished product the packing 45 may be thicker at 4^a than along the side walls in case slight stretching of such walls may have occurred. An advantage of my invention is that the leather required for making the packing need be of no greater 50 thickness than that called for in the finished product. The parts of the packing exposed to wear having been compressed and hardened in forming the packing results in increased life and utility thereof, 55 since the material is not cracked nor torn while being folded and danger of leakage past the packing in use is lessened.

With the three-part mold described any 60 desired inside diameter of one part may be used with any outside diameter of another part, and the inner ring 2 is the only one requiring change for producing two differ-

ent packings having the same inside diameter and different outside diameter or different thickness of leather or other material. 65 The parts of the mold may be made of any desired material, such as brass, cast or wrought iron or steel, or any desired combination of the same, or one or more of the parts may be made of suitable wood. The 70 parts of the mold may be used by hand operation or in a suitable press.

I do not in this application claim the mold for making U-packing herein set forth as the same is included in my divisional 75 application filed February 10, 1920, Serial Number 357,655.

Having thus described my invention, what I claim and desire to secure by Letters Patent is:—

1. The method of making U-packing consisting in folding a piece of suitable material to form a wall extending from the mid-portion of the material and then folding the protruding portion of said material reversely outside of and spaced from said wall and surrounding the same substantially parallel thereto.

2. The method of making U-packing consisting in folding a suitable piece of material 90 in substantially cup-like form having a protruding skirt-like portion and then folding the latter portion reversely around and outside of said cup-like portion and removing surplus material to produce a substantially 95 U-shaped ring having walls spaced apart.

3. The method of making U-packing consisting in first folding a disk of suitable material in cup-like form having a wall extending substantially at right angles to the 100 mid-portion of the disk with a skirt-like portion protruding from said wall, next pressing the skirt-like portion outwardly, then folding the skirt-like portion reversely around and outside of the first named wall, 105 removing the mid-portion of the disk to produce an annular U-shaped ring, and trimming the edges of the walls of said ring.

4. The method of making U-packing consisting in first forcing a portion of a disk 110 of suitable material within a ring to fold the disk in cup-like form with a portion protruding from said ring, pressing backwardly the portion of the disk protruding from the ring, then folding said protruding portion 115 of said material around said ring concentric thereof to produce concentric walls of said material, and removing the mid-portion of the disk and the surplus material at the edges of the concentric walls.

Signed at New York, in the county of New York and State of New York this 27th day of May, A. D. 1919.

THOMAS CROSSETT.
